2,662,488

SELF-PROPELLED RAILWAY CAR WITH
OPERATOR'S CABJoseph F. Clary, Glencoe, Ill., assignor to The
Budd Company, Philadelphia, Pa., a corpora-
tion of Pennsylvania

Application April 16, 1952, Serial No. 282,596.

9 Claims. (Cl. 105—62)

1

The invention relates to self-propelled railway cars and more specifically to the arrangement of the operator's cab and of the passage establishing communication with adjoining cars.

The object of the invention is a new self-propelled car eliminating certain objectionable features of known designs and achieving other additional advantages.

An objectionable feature of many known self-propelled railway cars consists in that they have so-called street car ends, that is: the operator is positioned directly behind the respective end wall. This is not only undesirable because it exposes the operator to great danger in case of accident but, for the same reason, is not permissible under the rules and regulations applying to certain railroad networks.

In the new car the operator is placed at a permissible, relatively safe location, while retaining communication between adjoining cars through their end doors as well as the payload space of known designs.

The above and further features, objects, and advantages of the invention will become apparent from the following description of several embodiments and from their illustration in the attached drawing.

In the drawing:

Fig. 1 is a small-scale, diagrammatic side elevation of a self-propelled railway car;

Fig. 2 is a sectional plan view of the same car;

Fig. 3 is an end elevation on a larger scale;

Fig. 4 is a fragmentary, sectional plan view on a larger scale showing the region surrounded by dot-and-dash lines 4 in Fig. 2, the section being taken along line 4—4 of Fig. 6;

Fig. 5 is a horizontal, fragmentary section on the scale of Fig. 4 taken along 5—5 of Fig. 6;

Fig. 6 is a diagrammatic, fragmentary, longitudinal section on the scale and taken along lines 6—6 of Figs. 4, 5, and 7;

Fig. 7 is a diagrammatic cross-section on the scale and taken along line 7—7 of Fig. 6;

Fig. 8 is a small-scale, diagrammatic side elevation of a self-propelled railway car representing a second embodiment;

Fig. 9 is a diagrammatic, fragmentary, longitudinal section, corresponding to Fig. 6 but illustrating the embodiment per Fig. 8;

Fig. 10 is a side elevation of a self-propelled railway car representing a third form of the invention;

Fig. 11 is a sectional plan view, the section being taken substantially along line 11—11 of Fig. 10;

2

Fig. 12 is an end elevation on a larger scale of the car shown in Fig. 10; and

Fig. 13 is a diagrammatic cross-section along lines 13—13 of Figs. 10 and 11 on the scale of Fig. 12.

The different embodiments illustrated in the drawing have a pair of supporting trucks diagrammatically indicated by their wheels 15, a horizontal floor 16, spaced at an appropriate height above the supporting trucks, side walls 17 with windows 18, and end walls 19. Each end wall has a passage door and opening 20 of standard dimensions and location so that it will line up with corresponding openings and doors of similar self-propelled cars or of other standard cars with which the new car may be coupled.

The power unit and the transmission are not shown in the drawing. Any known or otherwise appropriate construction and arrangement of these parts may be used. For instance, one or two combustion engines may be arranged under the longitudinal middle region of floor 16 and may be connected by any type of transmission with the wheels 15.

In the embodiment illustrated in Figs. 1 to 7, doors 21 centrally located in the side walls 17 lead to a vestibule 22 communicating with passageway or center aisle 23 of large passenger compartments. The passenger compartments have rows of double seats 24 between center aisle and side walls.

A partition or wall 25 spaced from the respective end wall 19 defines the outer end of the respective passenger compartment and is provided with an opening 26 for extending the center aisle to passage door 20. Between end wall 19 and partition wall 25, the center aisle is flanked by longitudinal partition walls 27, doors 28, and steps or stairs 29.

The steps 29 lead to the sections of a driver's cab 30, one section or cab on each side of center aisle 23. The cab and its sections are formed by a floor 31 arranged several steps above floor 16 though well below main roof 32, a transverse partition wall 33 extending between floor 31 and an end roof portion 34, a rear wall 35 extending between floor 31 and the rearward main or central roof portion 32, an upper front wall 36 provided with large windshields 37, a cab top or roof 38 merging by a sloping portion 39 into main roof 33, and upward extensions 40 of the side walls provided with windows 41.

The cabs or two sections 30 at each end of the car are in open communication with the stairs 29 and are in open communication with

each other above ceiling 42 of the car interior. Cab top 38 is preferably at full standing height above cab floor 31. Hand rails 43 at the sides of stairs 29 extend upwardly beyond the latter to facilitate entering and leaving the cab.

An operator's seat 43' is provided in each cab or section 30 on a horizontal portion 35 of wall 44. The control instruments 45 may be arranged on the front wall of the cab where, at appropriate height, a deadman's-bar 46 is arranged, the latter giving the operator a comfortable footrest if the seat is arranged too high to allow resting the feet on floor 31. A second (not shown) foot rest or stool may be provided for the other foot of the operator.

The spaces in front of the cab and below its floor may serve as storage lockers 47, restrooms 48, and lockers 49 for control equipment (not shown). A headlight 50 is provided in the center between windshield openings 37. Radiators 51 are arranged for the driving plant (not shown) are arranged on the central portion of roof 35, having about the same over-all height and cross-sectional outer dimensions as the operator's cabs 30 near the ends of the car. The roof portions 34 in front of the driver's cab may have about the same height and cross-sectional configuration as the roofs of standard cars so as to line up with the latter.

On account of the open communication of the driver's cab with the car interior, the cabs will be as comfortably heated, ventilated, and air-conditioned as the passenger compartments, without requiring additional installations.

The raised location of the cabs affords an excellent view over the track in front of the car for the operator and his assistant. In case of collision, the occupants of the operator's cab are not immediately endangered because their position will not be affected unless and until the end portion of the car in front of the operator's cab is crushed and the impact is great enough to destroy inwardly adjoining portions of the car. Evidently a great many if not the majority of collisions may lead to damage to the end wall but will not actually lead to destruction reaching the operator's cab.

The embodiment illustrated in Figs. 8 and 9 differs from the first embodiment mainly in that the radiators 52 are arranged directly behind the operator's cabs 30 and are enclosed in a housing 53 forming an extension of cab top 38 and merging at 54 into the central roof portion 35. Apart from this difference, the design is quite similar to the design per Figs. 1 through 7, the same numerals designating corresponding parts in both embodiments.

The embodiment per Figs. 10 to 13 has a simple car roof 56 of which the cab tops 57 constitute extensions. The centrally located radiators 58 project above roof 56 though to a lesser degree than in the preceding embodiments. The two sections 59 of the operator's cab are partly separated from each other in the upper region by a heating and air-conditioning duct 60 which also feeds the operator's cabs. The stairs 29 may, partly or completely, be recessed in the partitions or walls 27. The arrangement may be such that cab floors 31 are at less than standing height but that the recessed top step affords full standing height. The cabs are separated from the center aisle 23 by doors 61. The doors cover at least the recessed step or steps 29. Instead of a pair of windshields as in the preceding embodiments, the windshield has three window panes 62

which afford a still better, less obstructed vision. Two doors 63 in each side wall lead to a large vestibule 64 so as to speed up entry and discharge of passengers. Those features in which this embodiment and the preceding embodiment are substantially alike are again designated by the same numerals.

The invention is not restricted to the details of the illustrated embodiment but it extends to modifications and adaptations which will easily occur to those skilled in the art. For instance, the space between the operator's cab and the adjacent end wall may be formed as a vestibule with one or two side entry doors with or without a passage opening in the end wall.

What is claimed is:

1. Self-propelled railway car having an end wall provided with a passage opening for communication with an adjoining car, and having a longitudinal passageway leading from said opening into the interior of the car, the provision of a raised operator's cab on one side of and accessible from said passageway, said cab being spaced from said end wall and projecting above a roof portion of normal height and contour in front of it.

2. Self-propelled railway car having an end wall provided with a passage opening for communication with an adjoining car, and having a longitudinal passageway leading from said opening into the interior of the car, the provision of a raised operator's cab on one side of and accessible from said passageway, said cab being spaced from said end wall and projecting above a roof portion of normal height and contour in front of it, and steps, at least in part, recessed in the aisle wall establishing communication between said aisle and said cab.

3. Self-propelled railway car having an end wall provided with a passage opening for communication with an adjoining car, and having a longitudinal passageway leading from said opening into the interior of the car, the provision of a raised operator's cab on one side of and accessible from said passageway, said cab being spaced from said end wall and projecting above a roof portion of normal height and contour in front of it, and a door separating said cab from said aisle.

4. Self-propelled railway car having an end wall and a longitudinal passageway leading from said end wall into the interior of the car, the provision of a raised operator's cab on the side of and accessible from said passageway, said cab being spaced from said end wall and projecting above a roof portion between end wall and cab, the space below said cab being formed as a locker for control equipment.

5. Self-propelled railway car having an end wall and a longitudinal passageway leading from said end wall into the interior of the car, the provision of an operator's cab on one side of and accessible from said passageway, said cab being spaced from said end wall by a compartment of a width at least sufficient for permitting entry of a person, said cab being raised above the floor of the aisle and the car interior and projecting above a roof portion of about normal height and contour between it and said end wall.

6. Self-propelled railway car having an end wall and a longitudinal passageway leading from said end wall into the interior of the car, said passageway being spaced from both longitudinal sides of the car, the provision of a pair of raised operator's cabs, one on each side of and accessible from said passageway, said cabs being arranged

5

opposite each other, spaced from said end wall and projecting above a roof portion of normal height and contour in front of it.

7. Self-propelled railway car having an end wall and a longitudinal passageway leading from said opening into the interior of the car, said passageway being spaced from both longitudinal sides of the car, the provision of a pair of raised operator's cabs, one on each side of and accessible from said passageway, said cabs being arranged opposite each other, spaced a short distance from said end wall and projecting above a roof portion of normal height and contour in front of it, said cabs comprising a common upper part extending from side to side of the car and across said aisle.

8. Self-propelled railway car having an end wall and a longitudinal passageway leading from adjacent said end wall into the interior of the car, said passageway being spaced from both longitudinal sides of the car, the provision of a pair of raised operator's cabs, one on each side of and accessible from said passageway, said cabs being arranged opposite each other and spaced from said end wall, said cabs comprising a common upper part with a common cab roof extending from side to side of the car and across said aisle,

6

said cab roof projecting above roof portions of normal height and contour in front and rear of it, a radiator being arranged in rear of said cabs in a housing projecting upwardly beyond said roof portion in rear of said cabs and having about the same height and contour as said cab roof.

9. Self-propelled railway car having an end wall and a longitudinal passageway leading from adjacent said end wall into the interior of the car, said passageway being spaced from both longitudinal sides of the car, the provision of a pair of raised operator's cabs, one on each side of and accessible from said passageway, said cabs being arranged opposite each other and spaced from said end wall, said cabs comprising a common upper part with a common cab roof extending from side to side of the car and across said aisle, said cab roof projecting above roof portions of normal height and contour in front and rear of it, a radiator being arranged in rear of said cabs in a housing forming a rearward extension of said cab roof.
